Mich., a corporation of Michigan

Application March 14, 1945, Serial No. 582,606

7 Claims. (Cl. 292—169)

1

This invention relates to door latches, more particularly of the type which may be locked against operation from the outer side of the door, yet left in position for operation from the inner side of the door. In the art to which this latch is directed, such latches are generally known as bathroom locks. The present invention is concerned with an economical and simple latch structure easily installed on the door, requiring no expensive mortised holes to receive the lock housing, but only the boring of an elongated cylindrical opening at the edge of the door to receive the latch, and transverse openings through the door for the passage of the latch spindle at each end of which a door knob is secured for the manual retracting of the latch when the door is to be opened.

I have heretofore filed applications for patents on latch structures of the same general field of utility having Serial Nos. 549,644, and 564,211, filed August 16, 1944, and November 20, 1944, respectively. The present invention is directed to improvements in the structure thereof to provide a more sturdy and durable latch structure, one which is simpler in structure and one which is more effective in its operation with an attainment of all of the beneficial results which are recited in said previously filed applications.

An understanding of the invention may be had from the following description taken in connection with the accompanying drawings, in which,

Fig. 1 is a horizontal section through the latch structure with the interior latch mechanism in the position in which it may be operated from either side of a door on which installed.

Fig. 2 is a similar view showing the latch construction when it has been locked against operation from the outer side of the door, but may still be readily retracted from the inner side thereof.

Fig. 3 is a similar section illustrative of the automatic unlocking of the latch bolt which occurs when the outer projecting head of the bolt is pushed inward into the latch housing, as for example, should the door be closed with the parts in the position shown in Fig. 2.

Fig. 4 is a vertical longitudinal section through the latch mechanism, with the parts in the same position as shown in Fig. 1.

Figs. 5 and 6 are vertical transverse sections, Fig. 5 being taken substantially at the plane of the manually operated push bar used to lock the latch from operation at the outer side of the door, and Fig. 6 at a position outwardly thereof, and

Fig. 7 is a fragmentary horizontal section at the rear end portion of the latch structure, said longi-

2

tudinal section being offset from the plane of the section shown in Fig. 1 for a better disclosure of certain parts of the structure.

Like references refer to like parts in the different figures of the drawings.

The housing of the latch includes two members pressed from sheet metal, each having an intermediate portion 1 of a semi-cylindrical form and each being pressed inwardly to form vertical ledges 2 at the inner ends of said sections 1, and continued in channel shaped form therewith as indicated at 3, the outer side of one of said channel sections 3 having a horizontally disposed channel rib 4 (Fig. 5) pressed therefrom. At the inner ends of the channel sections 3 rollback housings are pressed outwardly as shown, from which short terminal channel sections 6 extend having inturned ends 7, which preferably may have interlocking connection as shown in the first 20 of said applications previously identified.

The semi-cylindrical intermediate sections 1 of the housing are continued at their outer ends in integral semi-cylindrical sections 8 of a smaller diameter, there being annular shoulders 9 between the sections 1 and 8. The two housing sections are placed together with their edges in contact, and the cylindrical outer end portion made by the two sections 8 is covered by the walls 10 of a cup made of sheet metal which has a bottom 11 with an opening therein for the passage of the outer head of a latch bolt. The metal at said opening is turned inward, as at 12, for forming a guide for one side of the bolt head. A relatively heavy plate 13 of metal is permanently secured to the bottom 11, it likewise having an opening for the passage of the bolt head, and the metal is turned inwardly, spaced from and parallel to the part 12 and constituting a guide 14 for the opposite side of the bolt head. Such structure of the 30 housing is substantially shown in the first filed of the above identified applications being modified by the formation of the channel shaped rib 4 between one of the vertical ledges 2 and the rollback housing 5 on one of the halves of the housing.

Within the housing a cup 15 of sheet metal has an annular flange 16 at its open end adapted to bear against the shoulders at 9. The bottom of 50 said cup is provided with an opening 17 therethrough at one side of the center. A heavy coiled compression spring 18 bears at one end against the flange 16, the outer end portion of the spring passing over the cup as shown. The inner end 55 of the spring bears against a plate 19 located

within the housing and normally lying against the inner sides of the ledges 2 described.

Said plate 19 has diametrically opposite ears 20 one of which passes through an opening of approximately the same cross sectional size as the ear made in one of the sections 1 of the housing, the other ear passing through an opening 21 in the opposite housing section 1 which opening 21 is elongated as shown (Figs. 1 and 2), permitting a limited tilting movement of the plate above the first described ear 20 as a pivot.

Said plate 19 has an opening therethrough to the same side of the center as the opening 17 is made through the bottom of the cup 15, and an ear struck from the plate at such opening on which a lever 22 is pivotally mounted between its ends to rock about a pivot pin 23 which passes through said ear and lever. One arm 24 of the lever extends outwardly from said pivot toward and into the opening 17 in the bottom of cup 15, and at its free end the inner edge of the arm is formed at an incline or angle as shown at 25. The extreme free end portion of the arm 24 enters the opening 17 which opening is a slot, and the arm is held and guided in its movements by the spaced sides of said slot opening.

The opposite arm of the lever 22 extends into the channel sections 3 of the housing and is formed with a projection 26 at one side which in the normal unlocked condition of the latch comes against the inner side of the web of the channel section 3 of one side of the housing (Fig. 7). Oppositely the lever has a projection 27 extending in the other direction which when said lever, as hereinafter described, is in a position to lock the latch against operation from the outer side of the door, comes against the web of the channel rib 4. Said projection is also provided at its inner end portion with a seat 28 which in the unlocked position of the latch mechanism receives a curved side of the pin 29 mounted upon and extending through the spaced flanges of the channel rib. The force of the spring 18 normally tends to hold the plate 19 in its position against the ledge 2 but when the lever 22 is moved from the position in Fig. 1 to that in Fig. 2 the spring 18 may yield sufficiently to permit plate 19 to rock, thereby disengaging the pin receiving seat at 28 from the pin 29 and bringing the free edge of the projection 27 against the bottom of the channel rib 4 with the pin 29 back of the projection 27. Thus the lever 22 is yielding retained in either extreme position to which it may be moved, and will hold either of such positions against aimless or accidental movement until a sufficient force is applied to rock the lever 22 from the position it may be in to the other position. The inner arm of the lever 22 terminates in a rearwardly extending finger 30 which in unlocked position is disposed centrally of the latch housing (Figs. 1 and 7). A pin 31 is mounted upon and extends laterally to one side of the inner arm of lever 22 being located between projections 26 and 27 (Fig. 7).

An actuating bar 32 of flat metal with a laterally turned ear at one end (Fig. 5) passes through the channel sections 3 of the housing and has a longitudinal movement, being guided by the passage openings for the bar in said channel sections in said movements.

A push bar 33 is screw connected at its inner end with the ear of the bar 32 and extends through an opening in the escutcheon plate associated with the door knob (not shown) at the inner side of the door.

The bar 32 at one side has a notch 34 cut therein one side of which is parallel to the length of the housing and the other inclined as shown, the pin 31 being received in the notch and bearing against the inclined side thereof, so that when the bar 32 is moved in the direction of its length from the position in Fig. 1 to that in Fig. 2, lever 22 is rocked about the axis of pivot pin 23 from the position of Fig. 1 and Fig. 7 to its locking position shown in Fig. 2.

The retracting latch spindle consists of two bars 35 and 36, square in cross section, which pass through openings in the ends of the roll-back housing portions 5 and are suitably joined at their meeting ends against separation but with a permission of independent rotation of each about their common longitudinal axis, specific detail of such connection not illustrated herein being fully shown and described in the earlier of my prior applications. In each of the roll-back housings a roll-back 37 of heavy sheet metal is mounted for rocking movement, each having an arc shaped flange 38 extending from its inner edge into the channel sections 3. The flanges 38 are spaced apart with the inner end of the locking lever finger 30, when it is at its central position as in Fig. 1, disposed between them. One of the flanges 38 at least, though both, may be supplied with it, has a recess 39 so that when on rocking the lever 22 from its position in Fig. 1 to that in Fig. 2 occurs, said finger enters the recess 39. It is the recess in the roll-back 37 located at the outer door side which is thus occupied by the finger 30, locking the spindle bar 35 against turning movement. It is of course to be understood that the bars 35 and 36 in practice are normally square in cross section and always are of a non-circular cross sectional form and pass through openings in the roll-backs of the same outline so that a turning movement of either spindle bar 35 or 36 about its longitudinal axis will rock its respective connected roll-back.

The latch bolt includes a normally projecting head 40 passing through the openings in the bottom 11 of the cap 10 and in the plate 13, and having the usual beveled portion to engage with a strike on a keeper provided on a door jamb or casing to receive it. A rod 41 is connected to the inner end of the head 40 and extends into the housing and through an opening in the bottom of the cup being provided at its inner end with a frustro-conical head 42 having inclined sides at substantially the same angle as the angular edge 25 of the arm 24. A relatively light coiled compression spring 43 surrounds the rod 41 between the head 40 and the bottom of the cup 15. Two bars 44 are connected permanently at their outer ends to the cup 15 and extend lengthwise of the housing inwardly from said cup and pass between the flanges 38 of the roll-backs, each having a transverse pin 45 passing therethrough so that the ends of the arc shaped flanges 38 of both roll-backs engage the projecting end portions of both pins. Thus on the manual rotation of either roll-back by engaging a door knob secured at the outer end of either of said spindle bars 35 and 36, the bars 44 are retracted with a compression of the heavy coiled spring 43, and an inward movement of the cup 15 which withdraws the head 40 of the bolt from a keeper with which it is engaged.

When the bar 32 has been moved from its position in Fig. 1 to that in Fig. 2, the roll-back 37 connected with the spindle 35 which extends 75 to the outer side of the door is locked against

movement by reason of the finger 30 entering the notch 39. The door thereupon cannot be opened by attempted turning of the knob at the outer side of the door. The inner side roll-back 37 is not locked and it may be readily operated from the inner side of the door with a retraction of the bolt in the usual manner.

When the door has been locked so that it cannot be opened from its outer side, the arm 24 of lever 22 has been moved to the position shown in Fig. 2, with the inclined edge 25 adapted to ride against the conical surface of the head 42. An operation of the latch bolt to withdraw it made from the inner side of the door causes the head at 42, when it is moved inwardly, to ride against the inclined edge 25 of arm 24, operating as a cam to turn the lever 22 to its neutral position (Fig. 1) with a consequent movement of the locking finger 30 out of the recess 39 of the roll-back flange in which it has been received.

If at a time when the door is open, the bar 32 was manually moved and thus locked the latch bolt against operation from the outer side of the door, upon closing the door with a consequent inward longitudinal movement of the head 40, rod 41 and rear head 42, the same automatic return of the lever 22 to neutral position occurs, as shown in Fig. 3.

The free end of the bar 32 in the case of an emergency may be engaged against by any suitable implement which may be passed through an opening made in the escutcheon at the outer side of the door and through an opening in the door in alignment therewith, the same as disclosed in my earlier filed applications.

Accordingly, with the structure described the parts are quickly and economically made largely from sheet metal, the installation on the door is of a simple and economical character. Such latch construction has safeguards against damage under all conditions of its use and is of value in use upon the inner doors of houses. The over all length of the latch is the same as that in the disclosure of my previously filed applications. In the operation the free ends of the bars 44 are stopped upon striking against the ends 7 of the housing parts, with a prevention of full rotation of the spindle members 35 and 36. The locking lever 22 is of a sturdy character and is held against lateral cocking or twisting, is guided and held at both end portions thereof and is one which is particularly simple, strong and durable in use.

The invention is defined in the appended claims and is to be considered comprehensive of all forms of structure coming within their scope.

I claim:

1. A latch comprising, an elongated housing open at one end, a two part operating spindle extending transversely through the inner portion of the housing, said spindle parts having independent rotative connection at their meeting ends within the housing, a latch bolt including a cup shaped member disposed within and across said housing, stop means carried by the housing for holding the cup member against outward movement beyond the stop means, spring means acting on said cup shaped member to normally move it against the stop means, retracting means connected to the cup-shaped member and extending to said two-part operating spindle, combined with independent means carried by each of the parts of said operating spindle for moving said cup shaped member inwardly on rotation of either part of the operating spindle in either direction,

5 a latch bolt head normally projecting through the open end of the housing, a rod secured to its inner end and extending through the bottom of the cup shaped member, a lighter spring means surrounding said rod between the bottom of the cup member and the inner end of the head, a locking lever pivotally mounted between its ends within the housing having an outwardly and inwardly extending arm, manual means for rocking said lever about its pivot, means connected with one of said spindle parts with which the inwardly extending arm of said locking lever is brought into holding engagement when the lever is rocked in one direction, and means carried by said rod at its inner end engageable with the forwardly extending arm of said locking lever for returning the locking lever to its initial position upon inward movement of said projecting bolt head.

2. A construction as defined in claim 1, said cup shaped member having an opening in the bottom thereof through which the forwardly extending arm of the locking lever may extend on spindle operated retraction of the latch bolt, the sides of said opening maintaining the locking lever in position against lateral movement.

3. A construction as defined in claim 1, the bottom of said cup shaped member having an opening into which the outwardly extending arm of the locking lever passes, means yieldingly holding the locking lever against movement in the direction of the length of the housing, and means against which the inwardly extending arm of the locking member engages for releasably maintaining the locking lever in either of the positions to which it is pivotally moved.

4. An elongated latch housing having an open end, a latch bolt having a head normally projecting through the open end of the housing, said bolt comprising two connected parts each independently spring actuated in an outward direction, said bolt head being connected with one of said parts and movable inwardly into the housing independent of movement of the other of said parts, and said bolt head being moved into the housing on inward movement of other of the latch bolt parts, separate means for independently and simultaneously retracting both parts of the latch bolt, manually operable from opposite sides of the latch housing and outside thereof, 45 a pivotally mounted locking lever within said housing having oppositely extending arms adapted when in one position to permit retraction of the bolt by either of said independently operable means, and when turned to another position locking one of said independently operable means against operation, and means carried by the part of the latch bolt with which the bolt head is connected engageable with one of the arms of said locking lever to move said lever from its operative locking position to unlocking position on inward movement of the bolt head, either when it is retracted upon movement of both parts of the latching bolt, or is moved with the part of the latching bolt to which it is connected independently of the other part of said latching bolt.

5. A construction as defined in claim 4, said locking lever being laterally guided at both sides, and at one end portion by adjacent sides of the housing to maintain it in substantially a single plane in its movements.

6. A construction as defined in claim 4, said locking lever at one end portion lying between spaced apart portions of the housing and with its sides closely adjacent thereto to maintain the lever in substantially a single plane in its move-

ments, and means at the opposite end portion of the lever, holding it at both sides against side movements.

7. A latch comprising a casing, a latch bolt slidably mounted in the casing and having a tail end extending into the casing, a spring to thrust said latch bolt outwardly, manual means for retracting the latch bolt, a locking lever pivotally mounted between its ends in said casing, the rear end of said lever being movable into locking engagement with said manual retracting means, a cam surface on the forward end of said lever movable into the path of said tail end of the latch bolt, and manual means for moving the rear end

of the lever into said locking engagement and at the same time moving said cam surface into the path of the tail end of the latch bolt.

ALBERT F. LICKTEIG.
